US0D1013012S

(12) United States Design Patent (10) Patent No.: US D1,013,012 S
(45) Date of Patent:  *Jan. 30, 2024

(54) CAMERA

(71) Applicant: Beijing Tusen Weilai Technology Co., Ltd., Beijing (CN)

(72) Inventors: Xiaoping Gu, Beijing (CN); Jie Sun, Beijing (CN)

(73) Assignee: BEIJING TUSEN WEILAI TECHNOLOGY CO., LTD., Beijing (CN)

(*) Notice: This patent is subject to a terminal disclaimer.

() Term: 15 Years

(21) Appl. No.: 29/751,359

(22) Filed: Sep. 21, 2020

(57) CLAIM

The ornamental design for a camera, as shown and described.

DESCRIPTION

FIG. 1 is a front perspective view of a camera showing our new design;

FIG. 2 is an enlarged front view of the camera;

FIG. 3 is a bottom view of the camera;

FIG. 4 is a top view of the camera;

FIG. 5 is a right-side view of the camera;

FIG. 6 is an enlarged rear view of the camera; and,

FIG. 7 is a left-side view of the camera.

The broken lines depict portions of the camera in which the design is embodied that form no part of the claimed design.

1 Claim, 7 Drawing Sheets
